UNITED STATES PATENT OFFICE.

HENRY H. LAMPERT, OF CHICAGO, ILLINOIS.

FORM CLAMP.

Application filed April 9, 1928. Serial No. 268,658.

The main objects of this invention are to provide an improved form of clamp adapted for attachment to a tie element; to provide a clamp having an improved form and arrangement of integral fastening means for securing the tie element to the clamp without the use of wedges or other separate fastening means; and to provide a clamp of this kind which is adapted for use as a form clamp in connection with concrete construction work and particularly for securing a tie band to a structural shape such as an I-beam.

Illustrative embodiments of this invention are shown in the accompanying drawing, wherein:—

Figure 1 is a transverse section of a girder mold having one form of clamp applied thereto.

Fig. 2 is a perspective of the clamp shown in Fig. 1 and showing the tie band as it appears before it is kinked.

Fig. 3 is a view similar to Fig. 2 but showing the bridge elements bent to kink the tie band.

Fig. 4 is a perspective of another form of clamp embodying this invention and showing a round wire tie.

Fig. 5 is a fragmentary section taken on the line 5—5 of Fig. 3.

In the construction shown, the improved clamps are used for securing flexible tie elements to a structural steel shape such as an I-beam 1. The girder mold is suspended from the I-beam by the tie elements and includes the usual soffit section 2, battens 3 and spacer blocks 4.

The tie element may consist of a flat metal band 5, as shown in Figs. 1, 2, 3 and 5, or of a round wire 6 as shown in Fig. 4. The size of the tie element depends upon the kind of mold to which the clamps are applied.

Referring to the drawings, two types of clamps are shown. The clamp shown in Figs. 1, 2, 3 and 5 is adapted to bear against one edge of the structural shape for attachment to both ends of the tie band or tie wire. The clamp shown in Fig. 4 is secured to only one end of the tie band or tie wire and therefore one is used at each end of the tie.

The clamp is preferably a sheet metal stamping and, in the form shown in Figs. 1, 2, 3 and 5 comprises a support 7 having a pair of bearing portions 8 and 9 disposed at substantially right angles to each other so as to be adapted to engage an edge of the struc-

tural shape as shown in Fig. 1. The support 7 is strengthened by reinforcing ribs 10 formed at the corner thereof.

Formed in the bearing portion 8, is an opening 11 adapted to receive a bight 12 formed in one end of the tie band 5. Extending through the bight 12, is a pin 13 which engages the inner face of the bearing portion 8 for securing this end of the tie band to the clamp.

Parts of the bearing portion 9 are struck out therefrom to provide recesses 14 and overlying bridge elements 15 spanning the recesses and spaced from the plane of the bearing portion 9 to permit the tie element to pass between the bridge elements and the bearing portion. The bridge elements 15 are bendable so that, when struck with a hammer or other suitable tool, they kink the tie element by forcing it into the recesses 14, as shown in Figs. 3 and 5. The bridge elements 15 may be formed in any desired size and shape to conform to the tie element with which the clamp is to be used.

In the embodiment shown in Fig. 4, the clamp comprises a bearing member 16 adapted to be supported on the upper face of the beam 1 and having one end thereof curled to provide a grip 17 adapted to embrace one edge of the beam flange.

Parts of the bearing member 16 are struck out to provide recesses 18 and overlying bridge elements 19. One end of the tie element passes between the bridge elements 19 and the bearing 16 and is kinked by pressure applied to the bridge elements.

The tie element is adjusted with respect to the clamp by a tool 20 comprising a shank which provides a handle and a head 21 on which is pivotally mounted a U-shaped locking jaw 22, which straddles the head 21 and which is pivotally secured thereto by a pin 23. The parts are arranged so that, when the jaw 22 is swung to an angular position relative to the handle, an opening is provided for receiving the tie element so as to permit the tool to grip the portion of the tie projecting beyond the clamp.

With the clamp shown in Figs. 1, 2 and 3, the tool is fulcrumed on the outer face of the bearing member 8 for pulling the running part of the tie relative to the clamp. With the form shown in Fig. 4, the tool 20 may be fulcrumed on the outer surface of the grip 17.

In setting up a mold with the clamp shown in Figs. 1, 2 and 3, one end of the tie is secured to the bearing 8 as shown in Figs. 2 and 3. The clamp is then supported on the top of the beam, as shown in Fig. 1 and the tie element is inserted through the battens 3 and soffit section 2 and is then looped around the beam. The free end of the tie is then inserted through the passage between the bridge elements 15 and the bearing 9 and is then secured to the tool 20.

The tool 20 is then applied to tighten the tie and, while the tie is held taut by means of the tool, the bridge elements 15 are struck with a hammer to kink the tie. The tool 20 may then be removed for use on other clamps and the projecting end of the tie is then bent so as to overlie the bridge elements as shown in Figs. 3 and 5.

With the form shown in Fig. 4, one end of the tie is rigidly secured to a clamp and the clamp is then placed on top of the beam. The tie element is looped around the beam and mold sections and the other end is then inserted through another clamp similar to the one shown in Fig. 4. This clamp is then applied to the opposite edge of the beam 1 and the tool 20 is then applied for pulling the tie relative to the second clamp. After the tie has been properly adjusted, the bridge

elements of the second clamp are bent to kink the tie.

Although but one specific embodiment of this invention has been herein shown and described, it will be understood that numerous details of the construction shown may be altered or omitted without departing from the spirit of this invention as defined by the following claim.

I claim:

A device of the class described comprising a support having a pair of bearing portions disposed transversely of each other for engaging adjacent sides of a structural shape, one of said portions having an opening for receiving a bight in one end of a tie element, a separate pin adapted to extend through the bight for engaging said one portion on respectively opposite sides of said opening, and a member struck out from the other of said portions to provide a recess and an overlying bridge element, said bridge element and last named portion defining a passage for the other end of said tie, said bridge element being bendable to kink said tie element into said recess.

Signed at Chicago this 6th day of April, 1928.

HENRY H. LAMPERT.
